(57) **CLAIM**

The ornamental design for concrete placer tool including octagonal pole handle, as shown and described.

DESCRIPTION

FIG. 1 is a perspective of a concrete placer tool including octagonal pole handle of our new design;

FIG. 2 is a front elevation of the concrete placer tool including octagonal pole handle;

FIG. 3 is a top plan view of the concrete placer tool including octagonal pole handle;

FIG. 4 is a bottom plan view of the concrete placer tool including octagonal pole handle;

FIG. 5 is a left side elevation of the concrete placer tool including octagonal pole handle;

FIG. 6 is a right side elevation of the concrete placer tool including octagonal pole handle; and,

FIG. 7 is a rear elevation view of the concrete placer tool including octagonal pole handle.

The broken lines depict portions of the concrete placer tool including octagonal pole handle in which the design is embodied that are not considered part of the claimed design.

1 Claim, 7 Drawing Sheets
